PUSH-BUTTON MECHANISMS

Alfred Döttlinger, Kirchdorf an der Krems, Austria, assignor to Jacob Ritter K.G., Brensbach, Odenwald, Germany, a firm of Germany

Filed June 16, 1959, Ser. No. 820,764

Claims priority, application Germany June 26, 1958

3 Claims. (Cl. 74—503)

The present invention relates to push-button mechanisms, the actuation of which alternately and successively moves a control element having a longitudinal axis from one to another of two axial locking positions, and is suitable for enabling the writing point of a writing implement to be advanced and retracted.

It is known to use push-button mechanisms for advancing and retracting the writing point and together therewith the ink reservoir of ball-point pens, the push-button mechanism comprising a push-button member slidably guided in a sleeve member, relative movement between the members being restricted by means of a captive ball retained between said members in a closed-ended or endless control groove in each of the mating surfaces of said members. In known ball-point pens an annular control groove is formed between the rear end of the pen barrel and the clip sleeve, the barrel and the clip sleeve together forming the sleeve member. The push-button mechanism can be assembled by inserting the captive ball in the control grooves before the clip sleeve is screwed on to the pen barrel.

According to one feature of the present invention a push-button mechanism comprises a push-button member slidably guided in a sleeve member, relative movement between said members being restricted by a captive ball retained in closed-ended or endless grooves in said members, one of said members having a ball-insertion groove open at one end and at the other end communicating with one of said control grooves, said ball-insertion groove being constricted at its opening into said control groove.

According to another feature of the present invention a push-button mechanism comprises a push-button member slidably guided for movement along a given axis in a sleeve member by mating surfaces in said members, and a captive ball retained between said members by a closed-ended or endless control groove in each of said mating surfaces thereof to restrict relative movement between said members, one of said control grooves extending transversely of said given axis and other of said control grooves having ball-locking stations spaced longitudinally of said given axis, and one of said members having in its mating surface a ball-insertion groove open at one end and at the other end communicating with the control groove of said one member, said ball-insertion groove being constricted at its opening into said control groove.

According to a further feature of the present invention a push-button mechanism comprises a push-button member slidably guided in a sleeve member by substantially cylindrical mating surfaces on said members, a captive ball retained between said members by a closed-ended or endless control groove in each of said cylindrical surfaces thereof, each of said grooves having a depth substantially equal to but not less than the radius of said captive ball, one of said grooves extending circumferentially of said cylindrical surfaces and the other of said grooves having ball-locking stations spaced longitudinally of said cylindrical surfaces and one of said members having in its cylindrical surface a ball-insertion groove extending from one end of the cylindrical surface to the control groove therein, the opening of said ball-insertion groove into said control groove being constricted.

2

In order to insert the captive ball in the mechanism it is only necessary to place the ball in the intersection of the end of the insertion groove on the end of cylindrical surface with the control groove of the member not containing the ball insertion groove and then to push the member containing the insertion groove into place, use of substantial pressure being required in order to overcome the effect of the constricted opening. The purpose of the constricted opening is to prevent the captive ball returning through the ball insertion passage during normal use of the push-button mechanism.

The push-button member may conveniently be manufactured from synthetic material by injection moulding. In this case the grooves in said push-button member are so formed as to facilitate the removal of the push-button member from the mould during manufacture. This may be achieved by forming the sides of the grooves in the push-button member so that they diverge towards the surface of said member. The sleeve member may also be manufactured from synthetic material by injection moulding.

The invention is further described by way of example with reference to the accompanying drawings in which:

FIG. 1 is a magnified cross section of the upper portion of a ball-point pen showing a push-button mechanism according to one embodiment of the present invention,

FIG. 2 is a magnified cross section of a second embodiment of a push-button mechanism suitable for use with a ball-point pen, and having different sleeve structure and arrangement,

FIG. 3 is a cross section similar to FIG. 1 illustrating a further embodiment of a push-button mechanism,

FIG. 4 is a magnified cross section of a ball-point pen having a push-button mechanism similar to that shown in FIG. 1, but showing alternative sleeve and barrel cap structure and arrangement,

FIG. 4a is a detail cross section to a slightly larger scale of the sleeve member of the push-button mechanism shown in FIG. 4,

FIG. 5 is a cross section on the line 5—5 of FIG. 1,

FIG. 6 is a cross section on the line 6—6 of FIG. 1, and

FIG. 7 is an electrical switch having a push-button mechanism similar to that of FIG. 1.

Referring first of all to FIG. 1, a push-button mechanism according to the invention comprises a push-button member 1, a sleeve member formed by a clip sleeve 2 of a ball-point pen and a captive ball 4. The convex cylindrical surface of the push-button member 1 cooperates with the inner concave cylindrical surfaces of the clip sleeve 2 in order to slidably guide the push-button member 1 along the axis of the sleeve 2. A control groove 6 is formed in the cylindrical surface of the push-button member 1 and a control groove 5 is formed in the cylindrical surface of the sleeve 2. The combined depth of the grooves 5 and 6 is substantially equal to but not less than the radius of the captive ball 4. The control groove 5 extends transversely of the axis of the push-button mechanism and extends substantially circumferentially of the clip sleeve 2 as in the embodiment of FIG. 1. The control groove 6 has two ball-locking stations 16 and 17 which are spaced longitudinally of the axis of the mechanism. The push-button member 1 is biased upwardly, for example by means of a spring (not shown in FIG. 1) so as to maintain the captive ball 4 in one or other of these stations. As will be apparent from FIG. 1, pressure on the push-button member 1 causes the captive ball 4 to move, relative to the member 1, along the left-hand portion of the control groove 6. Subsequent release of pressure from the push-button member

1 enables the ball to fall back to the ball-locking station 17. A further application to and release of pressure from the push-button member 1 allows the captive ball 4 to return to the ball-locking station 16 along the right hand portion of the control groove 6.

As can be seen from the drawings, the control grooves 5 and 6 are continuous grooves and therefore have no open ends. In order to enable the captive ball 4 to be initially inserted in the grooves the cylindrical surface of the push-button member 1 is provided with a ball-insertion groove 7. The ball-insertion groove 7 is open at one end and at its other end communicates with the control groove 6. The ball-insertion groove 7 is constricted at 8 where it opens into the control groove 6. The ball 4 is inserted in groove 5 through the lower part of groove 7 and is forced through the constriction 8 in the upper end of groove 7 and into groove 6 by the first actuation of the push-button into the groove during assembly of the member 1. The constriction 8 prevents the captive ball returning along the insertion groove 7 during normal use of the push-button mechanism.

The push-button mechanism of FIG. 1 is readily applicable to a ball-point pen such as is shown in FIG. 4. In FIG. 1 the clip sleeve 2 is screwed into the upper end of a pen barrel 3, a clip 10 being retained between the sleeve 2 and the barrel. The upper end of an ink reservoir 12 is biased by a spring to press against the end 11 of the push-button member 1. The push-button mechanism in FIG. 1 is shown in its position in which the writing point of the pen is retracted. Pressure on the member 1 to bring the captive ball 4 to its limit position 17x and release of the pressure for the spring bias and the cooperating groove shapes to bring the ball 4 into its ball-locking station 17 advances the point of the pen beyond the front end (not shown) of the barrel 3.

In FIG. 1 the push-button member 1, the sleeve member formed by the clip sleeve 2 and preferably also the pen barrel 3 are manufactured from injection-moulded synthetic material. The mechanism shown in FIG. 1 is a so-called "single-stage" mechanism where the ball 4, the groove 5 and alternately one of the pockets 16x or 17x defined in the upper transverse trace of the groove 6, cooperate as more fully explained in my pending patent application, Serial No. 848,081, to limit the downward movement of the push-button member 1. Pocket 16 in similar cooperation limits the upward movement of the push-button member 1.

In the embodiment of the push-button mechanism shown in FIG. 2 like parts in FIG. 1 are indicated by like reference numerals followed by the suffix "a". The clip sleeve 2a of FIG. 2 is however formed from metal. In FIG. 2 the groove 6a extends right around the push-button member 1a and the ball-insertion passage 7a is not only constricted at its opening 8a into the groove 6a but also opens downwardly in a funnel-like manner thus facilitating insertion of the captive ball during assembly. The mechanism shown in FIG. 2 is a so-called "single-stage" mechanism, where the ball 4a, the groove 5a, and the pocket 16xa defined in the upper transverse trace of the groove 6a cooperate to limit the downward movement of the push-button member 1a as more fully explained in my pending application, Serial No. 848,080. Pocket 16a in similar cooperation limits the upward movement of the push-button member 1a.

FIG. 3 shows a so-called "two-stage" mechanism in which the control groove 6b has a constriction 9b forming a limit position 17xb which can be felt as a stop when the mechanism is actuated gently. When the stop is felt, downward pressure on the push-button member is released and the ball 4b in cooperation with the groove shapes and the spring bias is brought to locking station 17b. A strong pressure on the push-button member 1b forces the ball past the constriction 9b to a second and positive limit position 16xb. When the pressure is released the ball 1b is returned to locking position 16xb by the spring bias

and shapes of the groove. In FIG. 3 again parts which are like those of FIG. 1 are indicated by like reference numerals with the suffix "b". However, the ink reservoir is indicated by 14 in FIG. 3.

5 In the ball-point pen shown in FIG. 4 an ink reservoir 14c is biased against a push-button member 1c by means of a spring 15. As can be more clearly seen in FIG. 4a the control groove 5c in the embodiment of the push-button mechanism of FIG. 4 is formed between a clip sleeve 2c and the upper portion of the pen barrel 3c. The sleeve member of the push-button mechanism of FIG. 4 therefore comprises both the clip sleeve 2c and the pen barrel 3c. A clip 19 is moulded integrally with the clip sleeve 2c. The lower edge 5d of the transversely 10 extending control groove 5c is formed by the upper end 18 of the pen barrel 3c and the upper edge 5c of the groove 5 is formed by an internal annular projection a shoulder 20 in the sleeve 2c which is screwed into the barrel 3c. The construction shown in FIGS. 4 and 4a has the advantage of simplicity. In FIGS. 4 and 4a parts 15 similar to parts of preceding FIGS. are indicated by like reference numerals with the suffixes "c," "d and e."

In order to facilitate removal from the mould after injection moulding of the push-button member 1 of the embodiment of FIG. 1, the control groove 6 and ball-insertion groove 7 are formed as shown in FIGS. 5 and 6. The sides 20, 21, 22 and 23 of the control groove 6 and the side 24 of the ball-insertion groove 7 are formed 20 divergent towards the cylindrical surface of the push-button member 1.

25 FIG. 7 shows an application of a push-button mechanism according to the invention for a purpose other than use with ball-point pens. In FIG. 7 a push-button mechanism according to the invention is used to open and close 30 switch contacts of an electric switch. A spring 15a is provided for biasing the push-button member, but if the switch contacts are sufficiently resilient it may be possible to dispense with the spring 15a.

35 In all the embodiments of push-button mechanisms 40 shown in the drawings the transversely extending groove is in the sleeve member and the groove with the longitudinally spaced ball locking stations is in the push-button member 1, but it is equally positioned to have a reverse arrangement, i.e. the transversely extending groove in the 45 push-button member and the groove with the ball-locking stations in the sleeve member. Moreover, the ball insertion groove could also be in the sleeve member.

The constriction 8 from the ball insertion groove 7 in the drawings may be formed at the end of a gradual taper 50 starting from the initial opening of the groove 7, as shown particularly in FIG. 1.

55 Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim:

60 1. A push-button mechanism comprising: a stationary sleeve means for enclosing and supporting the rest of the mechanism; a one piece push-button means longitudinally slidably in said sleeve means between axially spaced positions for alternating actuation therebetween; 65 opposing control grooves defined on said sleeve and push-button means, said grooves being shaped and positioned relative to each other to cross in an intersection that moves repetitively in a closed cycle as said push-button means is slidably actuated in said sleeve means between said axially spaced positions; a ball means adapted to fit between said opposing control grooves in said intersection and carried therein as said intersection moves in said closed cycle, said control grooves defining lock positions 70 for said ball means corresponding to said axially spaced positions, and said ball means cooperating with said 75

grooves for restricting said longitudinally slideable push-button means to alternate actuation between said locking positions; and a ball-means insertion groove for initially inserting said ball means in the intersection of said two control grooves, said insertion groove being defined and extending axially in said push-button means, said insertion groove having two oppositely disposed ends, one said end opening axially outwardly and there forming with said control groove of the sleeve means an intersection into which said ball is initially placed, and the other said end tapering radially outward to form a constricted inner end opening into the control groove on said push-button, said constriction requiring an application of axially directed force to said ball means to push it past said constriction and into the intersection of said control grooves, said axially directed force being applied by the initial actuation of said push-button means.

2. A push-button mechanism as described in claim 1, said push-button means consisting of an integral piece of molded plastic and having a cylindrical periphery formed with said insertion and control grooves, said grooves on said push-button means comprising at least two peripherally spaced portions which extend substantially in the longitudinal direction of the push-button means and have side walls diverging to said periphery to facilitate the removal of the push-button means from a mold.

3. A push-button mechanism as described in claim 1, said sleeve means consisting of a barrel top member formed with an internal collar having a lower end face

defining an upper edge of said control groove on said sleeve, said mechanism further comprising a lower barrel member having an upper end face and said barrel members being screw-threadedly connected and said lower end face of said top member forming said shoulder of said lower member, said upper end face being spaced below said lower end face to define a lower edge of said control groove on said sleeve means, said ball means having a diameter substantially exceeding the depth of each of said control grooves, said push-button means having a stop disposed above said control groove on said push-button means, said top member having a cylindrical inside surface extending from said internal collar downwardly and without increase in diameter for a length which is at least equal to the axial distance from said stop to the lowermost point of said control groove on said push-button means.
